CLAIM

The ornamental design of a winch housing, as shown and described.

DESCRIPTION

FIG. 1 is a perspective view of a winch housing showing my new design;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The features shown in broken lines in the drawing figures depict environmental subject matter only and form no part of the claimed design.

1 Claim, 7 Drawing Sheets# US D914,321 S
